QUICK ACTING HOOK

Marvin O. Miller, El Cerrito, Calif., assignor to the United States of America as represented by the Secretary of the Navy

Filed Apr. 24, 1963, Ser. No. 275,468

3 Claims. (Cl. 294—84)

(Granted under Title 35, U.S. Code (1952), sec. 266)

The invention described herein may be manufactured and used by or for the Government of the United States of America for governmental purposes without the payment of any royalties thereon or therefor.

This is a continuation-in-part application of United States Patent No. 3,109,185, filed April 18, 1962, entitled Apparatus and Method for Launching and Recovering Lifeboats in Rough Seas.

This invention relates generally to quick acting and self closing hooks. More specifically it covers a manually maneuvered, normally open hook, which automatically closes upon contact with an object to be held and is adapted to be manually released and controlled by a lanyard when the load is removed. The use of such a hook is particularly applicable to rapid boat recovery systems especially when launching or recovery is made in open water where waves and currents affect such work. The hazards of such an operation are directly attributed to the lack of speed and facility of the device for coupling the load to the hoisting apparatus.

The general purpose of the proposed hook per se is to remove the hazardous condition pointed out in the preceding paragraph and provide an improved type hook.

An object of the subject device is to provide a hook adapted to automatically close and catch when manually maneuvered into contact with a load bar.

Another object is to provide a vertically suspended hook body having a horizontal hook opening and a foam rubber grip attached to said body so that the suspended hook opening can be maneuvered with greater facility and safety into engagement with a load bar.

Another object is to provide a U-shaped hook body and an arcuate latch arm pivoted to said body so that the internal curved surface of the body and the external curved surface of the latch arm will coincide when closed and will provide full arcuate bearing contact under load.

Another object is to provide a catch arm assembly connected to said arcuate latch arm but on the opposite side of the pivot from said latch arm.

Another object is to make the catch arm assembly heavier than said arcuate latch arm so that its weight will tend to open the latch for sidewise engagement with a load bar.

Another object is to form the end of the hook body so that it will provide a combination keeper for the catch plunger in a closed position and a direct contact limit stop for the latch arm in fully open position.

Another object is to provide a latch spring under tension between the latch arm and said body so that it will urge the latch arm into fully open position, cocked for engagement with a load bar.

Another object is to provide lanyard means for retraction of the catch plunger and positively opening said hook so that it may be remotely operated for manually opening the arcuate latch at a safe distance.

Another object is to provide a hook which will close when subjected to a load and will be retained in a closed position by a spring operated plunger catch even though the load forces are reduced or removed entirely.

Another object is to provide a hook manually opened remotely by a lanyard and retained in this open position by spring action between the body and latch arm as well

2

as the resultant of forces set up by the pivoted latch arm and catch arm assembly.

Additional objects reside in the combinations of elements, arrangements of parts, and features of construction, all as will be more fully pointed out hereinafter and disclosed in the accompanying drawings, wherein there is shown a preferred embodiment of this inventive concept. In the drawings:

FIG. 1 is a perspective view of the hook in a closed position;

FIG. 2 is a front elevation of the closed hook shown partially in section and containing a load bar; and

FIG. 3 is a front elevation of the hook partially covered with a resilient material and open, ready for engagement with a load bar.

In detail, the hook 11 comprises a U-shaped body 12 designed for side opening as shown in FIG. 3, and adapted to be moved manually into engagement with a load bar 33 connected to any type of load usually an unsteady moving load to be lifted by said hook 11. A latch 13 is pivoted at pin 14 to said body 12 and comprises an arcuate latch arm 16 and a catch arm assembly 17.

One end of the body 12 is formed into a hook 18 which serves as a combination keeper for plunger 19 of the catch assembly 17 and also as a limit stop for tip 20 of the arcuate latch arm 16. In an open position FIG. 3 the tip 20 is stopped by hook 18 so that the quick acting, automatic closing hook will be cocked into the open and preferred position for sidewise engagement manually with a load bar.

The detail design and structure of the combination arcuate latch arm and catch assembly, pivoted to the body incorporates many of the novel features of the invention. First the arcuate latch arm 16 is provided with an arcuate external surface 28 designed to coincide with the internal arcuate surface 29 of the body 12. By the aforesaid detail the load carried by the latch arm 16 is uniformly transferred to the hook body 12 without distortion of said latch arm 16.

The latch arm 16 is pivoted to hook body 12 at 14 and the catch arm assembly 17 is fastened to said latch arm 16 but disposed on the opposite side of the pivot 14. The catch arm assembly 17 includes a plunger catch 19 closed by plunger spring 21 so as to engage the keeper hook 18 and maintain the latch arm 16 closed and secure the load bar 33 in its lifting position, FIG. 2.

The plunger 19 is provided with a link 22 adapted for retraction of the plunger catch 19 against the tension of spring 21 and releasing the plunger 19 from the keeper hook 18 to open the latch 13. A lanyard 23 is attached to the link 22 so that the plunger catch 19 can be manually released at a point remote from the hook proper. Such a hook 11 may be employed for quick attachment to a boat at sea during rough water and the danger of injuring the operators hands or fingers are greatly reduced by the remote means for opening the hook. For the same reason, a resilient, shock-proof grip such as sponge rubber 32 is desirable as a cover for the handle 31 to facilitate maneuvering the hook 11 into engagement with the load bar 33.

If on first try the latch arm 16 is accidentally closed, continued tension on the lanyard 23 will immediately open the latch arm 16 and catch arm 17, ready for a second try at engagement with the load bar 33 when the opportunity presents itself.

Another object of this invention is to design the curvature of the arcuate surface 30 of latch 13 against which the load bar 33 bears directly so that the vertical direction of force 34 of the load bar 33 will bear inside the body pivot point 14 thereby tending to retain the latch in a closed position regardless of the extent of the load. Therefore by supporting the hook 11 by a clevis pin through

the top pivot point 24 the vertical pull by a load on bar 33 will set up a moment of force tending to close the latch 13 and secure the load bar therein.

Still another feature of the design is the encased formed torsion spring 27 mounted on the end post 25 of body 12 and encircling the pivot 14 and bearing under tension against the internal surface 29 of latch arm 16. This spring 27 is provided for assisting the weighted catch arm assembly 17 in maintaining the latch arm 16 open when not under load. In other words, when the latch arm 16 is once opened and cocked for sidewise movement to engage a load bar, the spring 27 will retain the latch in its open position and steady it to prevent accidental closing.

What is claimed is:

1. Hook apparatus adapted to be suspended from above and comprising:
  - a U-shaped body portion having upper and lower legs and an interconnecting arcuate web, suspension-receiving means provided on said upper leg in position for causing said suspension to dispose the body portion with the U-opening facing substantially laterally outwardly,
  - handle means carried by said web and extending laterally outwardly of the web in a direction opposite to said U-opening,
  - a U-shaped latch and catch assembly integrally formed of a catch arm, an arcuate latch arm and an interconnecting arcuate web, means carried by said lower leg of the body portion for pivotally carrying said latch and catch assembly on a horizontal axis, said axis extending through said assembly web and being offset outwardly of said assembly web center toward said U opening,
  - said assembly being mounted in position for swinging outwardly from a closed position, wherein said arcuate latch arm abuts said arcuate body portion web and said catch arm traverses said U-opening of the body portion, into an open position wherein said U-opening is exposed,

hook detent means carried at the outer end of the upper leg of the body portion for engaging the latch arm in said open position whereby said outward swinging movement of the latch arm is limited, resilient means normally urging said latch and catch assembly into said open position, retractable plunger means carried at the outer end of said catch arm for engaging said hook detent means when said catch arm is in said closed position, means resiliently urging said plunger means outwardly of said catch arm, and means operable from a remote position for manually retracting said plunger, said plunger having a cam surface adapted to engage the outer end of said upper leg during a closing movement of said latch and catch assembly, said engagement depressing said plunger for permitting the plunger to move past said outer end into a resiliently-held engagement with said detent means, whereby said catch arm automatically closes and interlocks.

2. The apparatus of claim 1 wherein said remotely-operable manual means is formed of a lanyard secured to said plunger means.

3. The apparatus of claim 1 wherein said catch arm is heavier than the latch arm whereby the added weight tends to swing the assembly into its open position.
